GUIDE FOR INDICATING THE FECUNDITY RHYTHM IN WOMEN

Emmett J. Culligan, Fort Wayne, Ind.

Application May 8, 1933, Serial No. 669,811

9 Claims. (Cl. 40—110)

My invention relates to a guide for indicating the fecundity rhythm of women, and has for its object to provide a mechanism which may be set at the beginning of the menstrual period of any woman and which will visually indicate the times when conception is possible and probable and the times when conception is impossible or unlikely to take place.

Recently disclosed scientific investigations have brought to light the fact that with the average woman who is normal in the menstrual cycle within limits of from twenty-six to thirty-one days, ovulation takes place, not as heretofore supposed at or about the time of menstruation, but at a time some thirteen to fifteen days before the beginning of menstruation. These investigations and scientific findings have revealed that with normal women, as above recited, the time of ovulation may vary two or three days, and that spermatozoa may remain viable for a period of about two days after being deposited. There is thus only a period of five to six days during the cycle of such a normal woman in which fecundation can take place, and abstention during that period will prove reasonably certain assurance against undesired conception. On the other hand, for those married people who desire children, that period is the time when conditions most favorable to conception exist, and is the proper time to undertake to bring it about.

Even though these recently discovered facts are known, their application in any particular place is rendered more or less impracticable by reason of the difficulty in remembering from time to time the considerably extended periods involved. It is the object of my invention to provide a slide rule embodying calibrated date lines covering not less than a full two-month period of each of the four different duration months of the calendar, to wit, twenty-eight day months for usual Februarys, twenty-nine day months for leap-year Februarys, thirty-day months for April, June, September and November, and thirty-one day months for January, March, May, July, August, October and December, and in combination with these date calibrations to provide a slide member on the rule with adjustments for menstruation cycles of from twenty-six to thirty-one days, and from regularity to four-day irregularity which may be conveniently set, so that when the front of the slide portion is set to the calibration line immediately following the date of beginning of menstruation there will be positioned along the aforesaid date calibrations distinctive portions of the slide member indicating the exact days when

conception is most probable, when conception is possible and when conception is either impossible or extremely unlikely of occurrence.

The full objects and advantages of my invention will appear in connection with the detailed description thereof and are particularly pointed out in the claims.

In the drawing illustrating applications of my invention,—

Fig. 1 is a plan view of a cylindrical rule member embodying four sets of date calibrations and a cylindrical slide thereon with adjustable members available for both differences in cycle and for irregularities common to the cycle. Fig. 2 is a plane projection of the main slide member showing the arrangement of indications for making adjustments for different length cycles and for irregularity. Fig. 3 is a plane projection of the adjustable piece mounted on the slide which indicates on the date line calibration the dates of most probable and possible conception as adjusted for regular or up to four-day irregular cycles. Fig. 4 is a section on line 4—4 of Fig. 1. Fig. 5 is a section on an enlarged scale on line 5—5 of Fig. 1. Fig. 6 is a plan view of a flat slide rule embodying the four sets of date calibrations and the flat slide thereon operating in the same manner as on the cylindrical rule of Fig. 1 and also is in effect a plane projection of the arrangement of date extensions of Fig. 1.

As shown in Fig. 1 a cylindrical member 10 which may be a metal rod or metal cylindrical shell has calibrated thereon a series of date lines 11 located about the cylinder at right angle quadrant points thereon, each of said date lines upon said cylindrical surface corresponding with the twenty-eight, twenty-nine, thirty and thirty-one day month calibrations 12, 13, 14, and 15 of Fig. 6. The calibration 11 shown is for a thirty-day month, corresponding with calibration 15 of Fig. 6. Each line of calibrations therefore embodies sixty-two date numbers, being two full thirty-one-day months and in excess of two full thirty-day, twenty-nine-day and twenty-eight-day months. Slidably mounted upon the member 10 is a split cylinder 16 which has its edges separated to provide a longitudinal slot 17 of sufficient width to take along the boundary edges of the date line calibrations of any month selected, as clearly shown in Fig. 1. The member 16 is provided on one of the edges of said slot with two series of indentations or notches 18, 19. Mounted to slide upon the slide 16 are two split cylinders 20 and 21, each provided with a pin 22 and 23, the pin 22 to take in the notches 18 to adjust the position

of the cylindrical piece 20 and the pin 23 being adapted to take into the notches 19 to adjust the notches on the cylindrical piece 21. The piece 20 is provided with an open slot 24 and the piece 21 with an open slot 25 of a width similar to that of the slot 17 and adapted to register therewith when the pin 22 is seated in one of the notches 18 and the pin 23 is seated in one of the notches 19. Corresponding to each of the several notches 18 are limit lines marked upon the slide 16, with notations, "31-day cycle", "30-day cycle", "29-day cycle", "28-day cycle", "27-day cycle" and "26-day cycle" as appears in Fig. 2, and the several notches 19 correspond with limit lines on the piece 16 designating respectively "regular cycle", "one-day irregular", "2-day irregular", "3-day irregular" and "4-day irregular".

In use the piece 20 will be adjusted by means of the pin 22 in a notch 18 so that the rear limit 26 of said piece will register with the limit line 27 immediately in front of the particular menstruation cycle of the subject using the rule, as for example immediately in front of the limit line 27 which exposes the caption "28-day cycle", as in Fig. 1. By means of pin 23 in one or the other of notches 19 adjustment will be made so as to bring the rear line 28 of piece 21 into register with one of the limit lines 29 in front of the designation of the regularity cycle, as in front of the designation "Regular cycle" as in Fig. 1. On the date when menstruation begins the slide 16 will be moved along the rule to bring the front edge 30 of the piece 20 thereon into alinement with the rear boundary line of the date block upon which menstruation begins. That is, assuming that menstruation begins on the fifteenth of a thirty-day month, line thirty will be brought into register with the rear line of the fifteen block, as in Fig. 1. A ring clamp 32 provided with a setscrew 33 encircles the split cylinder piece 16 and thereby the piece 16 will be clamped in position on the rule after the above-mentioned setting. In this position the piece 21, which is preferably distinctively colored, as red or black, will with its outer limit lines 28 and 34 clearly indicate on the date line set of calibrations the eight days during which for the particular subject conception is probable or possible. The limits 30 of piece 20 and 35 of the slide 16 will indicate upon said date line calibrations those dates outside of the period of probable or possible conception wherein fecundation and conception are impossible or unlikely to take place. The piece 21 preferably carries notations "Fertile", "Conception possible", "Ovulation" with an indication of the probable date of ovulation, "Most fertile dates, Conception probable", indicating the days in which conception is most likely to occur.

Thus, when the adjustments heretofore referred to have been made for the menstruation characteristics of the subject, and the setting has been made and locked in position upon the day of beginning of menstruation, there is at all times available to the subject a simple and visual indication, applicable to the particular menstruation cycle and characteristics of the individual subject, of those days and dates when conception is possible and most probable, and of those days and dates in which conception is impossible or not likely to occur. And this setting can be made upon the rule when menstruation begins on any day and date of any of the different month periods comprising the calendar in use.

The same adjustments and settings are prac-

tically possible on the flat slide rule of Fig. 6, wherein the slide comprises a slotted plate 36 with portions embracing the edges of the main rule member 37 and with slide pieces 38 and 39 thereon corresponding to slide pieces 20 and 21 on the piece 16.

I claim:

1. A device for indicating probable conception dates comprising a member having thereon calibrations and intervening date indications covering the dates of two calendar months for each of the four possible sets of month durations in a year, a member associated therewith and adapted to be set at any one of the date indications of any of said month terms and to extend over all date indications thereon covering a complete menstrual cycle, and means on said member delimiting and indicating the days and dates within the said menstrual period of possible and most probable conception and for indicating all the days and dates of probable physiological sterility.

2. A device for indicating probable conception dates comprising a member having thereon calibrations and intervening date indications covering the dates of two calendar months for each of the four possible sets of month durations in a year, means associated therewith and adapted to be set at any one of the date indications of any of said month terms and to extend over all date indications thereon covering a complete menstrual cycle, means for indicating the days and dates within the said menstrual period of possible and most probable conception, and means for expanding or contracting said last-named indicating means to cover longer or shorter periods to accommodate for known irregularities of said menstrual cycle.

3. A device for indicating probable conception dates comprising a member having thereon calibrations and intervening date indications, means associated therewith adapted to be set to one of said date indications and to extend over all said date indications covering a single menstrual period, means for indicating the days and dates within that period of possible and most probable conception, and means for increasing or decreasing the extent of said associated means to change the number of date indications embraced thereby to correspond with different lengths of menstrual periods.

4. A slide rule embodying four sets of calibrations and intervening indications of the dates of two consecutive months for each of the possible month durations of any year, a piece slidable thereon and adapted to have its front end register with any calibration of the dates of the first of any of said sets of months, said piece being of such a length as to include between its limits the days and dates of a complete menstrual period from the beginning to the end thereof and to expose all said dates alongside an edge of said piece, means on the piece delimiting and indicating the days and dates of possible and most probable conception and for indicating all said dates which are of probable physiological sterility, said means being related to the beginning and the ending of a menstrual period, and means to lock the piece where set.

5. A slide rule embodying calibrations and intervening indications of the dates of two consecutive months, a piece slidable thereon and adapted to have its front end register with any calibration of the first month dates, said piece being of such length as to include between its date limits the days of a complete menstrual period, means on

the piece indicating the days and dates of possible and most probable conception, and means to change the effective length of said piece to accommodate it to menstrual periods of different lengths.

6. A slide rule embodying calibrations and intervening indications of the dates of two consecutive months, a piece slidable thereon and adapted to have its front end register with any calibration of the first month dates, said piece being of such length as to include between its date limits the days of a complete menstrual period, means on the piece indicating the days and dates of possible and most probable conception, and a second piece slidable on said first-named piece with means thereon to hold it positioned to change the effective length of said first-named piece to accommodate to menstrual periods of different lengths.

7. A slide rule embodying calibrations and intervening indications of the dates of two consecutive months, a piece slidable thereon and adapted to have its front end register with any calibration of the first month dates, said piece being of such length as to include between its date limits the days of a complete menstrual period, means on the piece indicating the days and dates of possible and most probable conception, and a second piece on the first-named piece to indicate days and dates of possible and most probable conception, and means to permit movement and positioning of said second piece to accommodate for irregularities in said menstrual period.

8. A slide rule embodying calibrations and intervening indications of the dates of two consecutive months, a piece slidable thereon and adapted to have its front end register with any calibration of the first month dates, said piece being of such length as to include between its date limits the days of a complete menstrual period, means on the piece indicating the days and dates of possible and most probable conception, a second piece slidable on said first-named piece with means thereon to hold it positioned to change the effective length of said first-named piece to accommodate to menstrual periods of different lengths, and means to permit movement and positioning of said second piece to accommodate for irregularities in said menstrual period.

9. A device for indicating probable conception dates comprising a cylinder having thereon and at quadrant points thereabout calibrations and intervening date indications covering two full months of from twenty-eight to thirty-one days, a semicylindrical slide thereon with a slot adapted to embrace any one of said sets of calibrations, and of such length that when its front edge is set adjacent the rear calibration of the beginning date of menstruation it will extend throughout its length over all the days of a single menstruation period, means on said slide for indicating the days and dates within that period of possible and most probable conception, a piece on the slide and means for moving said last-named piece to accommodate for irregularities in the menstrual period.

EMMETT J. CULLIGAN.
